UNITED STATES PATENT OFFICE.

ELSIE C. BENSON, OF SEATTLE, WASHINGTON.

PORTABLE BATH CABINET.

Application filed January 12, 1925. Serial No. 1,993.

The invention is a portable bath cabinet which has convenient shelves and a rack adjacent the tub, a hinged cover with sliding supports, and suitable drawers and compartments below the tub.

The object of the invention is to provide a bath cabinet that may also be used as a dresser or the like which is provided with means above the tub for holding articles.

Another object of the invention is to provide a cabinet having a hinged cover with a small bath tub directly under the cover and having a compartment below the bath tub in which is a receptacle so that the bath tub may drain into it.

And a still further object is to provide a portable bath cabinet which is of a simple and economical construction.

With these ends in view, the invention embodies a cabinet resembling a dresser having a hinged top with sliding supports under it, a small bath tub under the cover and a rack with shelves and a rod, at the rear of the stationary portion of the top.

Other features and advantages of the invention will appear from the following description taken in connection with the drawings, wherein:

Figure 1 is a front view of the cabinet with the top open.

Figure 2 is an end view with one end of the rack at the top omitted.

Figure 3 is a cross section through the cabinet.

Figure 4 is a detail showing the arrangement of the tub and receptacle below it.

In the drawings I have shown my cabinet as it would be constructed wherein numeral 1 indicates the frame, numeral 2, the tub, and numeral 3, the shelf rack at the top.

The frame 1 may be constructed in the form of a dresser with drawers 4 as shown in Figures 1 and 3, and a compartment 5 into which a receptacle 6 may be placed so that the tub 2 may drain into it. The dresser may be provided with a stationary top 7 and a hinged top 8 which may be hinged to the stationary top at the point 9. The stationary top 7 is provided with an opening 10 into which the tub 2 may be placed and at the rear of the cover 7 is a shelf rack 3.

Just below the stationary cover 7 is a sliding support 11 which is constructed with a cross member 12 and two bars 13 and 14, which are held in cleats 15 and 16 as shown in Figure 3. It will be seen that the support 11 may be moved into or out of the frame 1 to support the hinged cover 8 when desired.

The rack 3 is constructed with ends 17 and 18, a back 19, shelves 20 and 21 and a rod 22. This rack is readily attached to the top and it will be seen that the shelves provide handy space for laying articles of clothing or the like while bathing the child. The rod at the top of the rack may also be used for supporting wash cloths, towels or the like.

It will be understood that other changes may be made in the construction without departing from the spirit of the invention. One of which changes may be in the arrangement of the drawers or compartments, another may be in the design of the tub, another may be in the arrangement of the receptacle for the drainage, and still another may be in the design or arrangement of the shelf rack at the top.

The construction will be readily understood from the foregoing description. To use the device, it may be assembled as shown, and it will be seen that when it is desired to bathe a child or wash clothes or the like, the top may be opened as shown in Figure 1 and the tub filled with water. It will be seen that with the device arranged in this manner, it will be particularly convenient as the clothes or the like may be placed on the shelves on the rack 3 so that they will be handy, and also with the top 8 opening to the position shown in Figure 1 an unusually large amount of space will be provided to place other clothes or objects; while at the same time this large shelf may readily be placed within the limits of the cabinet when not in use.

Having thus fully described the invention, what I claim as new and desire to secure by Letters Patent, is:

In an article of furniture of the character described comprising a cabinet with a wash tub in the upper part thereof, drawers in the lower portion of the cabinet and sta-

tionary shelves extending upward from the rear of the said cabinet; a pair of parallel beams slidably held in channel tracks below the cover of the said cabinet, and a cross beam connecting the said parallel beams at one end and having a knob thereon connecting the ends of the said parallel beams,

10
said cross beam representing a drawer front at the end of the said cabinet and adaptable to draw the parallel beams outward to support a second cover hinged to the end of the top of the said cabinet when the said cover is used as a shelf.

ELSIE C. BENSON.
